RADIATOR FLUSH

Paul Victor Keyser, Jr., New York, N. Y., assignor
to Socony-Vacuum Oil Company, Incorporated,
New York, N. Y., a corporation of New York

No Drawing. Application October 15, 1935,
Serial No. 45,099

3 Claims. (Cl. 87—5)

This invention relates to a novel composition for use in cleaning the radiator and other parts of the cooling system of an internal-combustion engine.

In such cooling systems a solid sediment or encrustation gradually collects, consisting of iron rust, dirt, mineral matter from the water, etc., usually mingled with some oil or grease from the circulating pump. It is well known that such 10 deposits can be effectively removed by subjecting them to the solvent and penetrating action of some oily material containing or consisting of saponifiable oil or free fatty acid, and then subjecting the mixture of solids and oil to the action 15 of an alkaline solution by which the oil or, the fatty acid is saponified, with the result of disintegrating the mass and bringing its constituents into a state of emulsion and suspension in which they can be flushed away.

In order to bring the solvent oily material into contact with the deposits throughout the cooling system, without the necessity of using it in the great volume necessary to fill the system, the oil has heretofore been introduced in a small 20 quantity while the system is substantially full of water, and the circulation of the water, while the engine is running, has been utilized to carry the oil throughout the system. For success in this mode of operation, it is necessary that the 25 constituents of the oily mixture be so selected and proportioned that the mixture has very nearly the same specific gravity as water, at the temperature of use. It has also been necessary, as the method has heretofore been practised, to add the alkali to the cooling water as a second and 30 distinct operation, after sufficient time has been allowed for the penetrating action of the oil.

One object of the present invention is to produce a composition, for the purpose in question, in which all of the necessary ingredients 35 and reagents are contained so that they may be introduced in the cooling water as a single operation, and another object is the production of a composition in which the solvent oily material 40 is originally held in emulsion with a water solution, so that, when introduced into the cooling water, the oily material is quickly disseminated therein.

I have discovered that the foregoing objects 45 may be attained by combining the following elements:

1. Unsaponifiable oily material which has the desired solvent and penetrating action.

2. Water.

55 3. An emulsifying agent which is soluble in the

oil, and thus permits the production of a stable water-in-oil emulsion.

4. A reagent which, at normal atmospheric temperature, is inert towards the other components, but which reacts, at the elevated temperature of the cooling water after the engine has been running for some time, to reverse the emulsion and produce an oil-in-water emulsion.

Various oils and organic solvents, insoluble in water, are known to have the required penetrating and solvent action. Light petroleum distillates, such as kerosene may be used, or coal-tar solvents, also chlorinated hydrocarbons such as trichlorethylene, tetrachlorethylene, ortho-dichlor benzene and chlorinated di-phenol. These 10 solvents may be used alone or in any combinations consistently with the described principle of operation, as they are not required to enter into chemical reaction with the other ingredients.

The emulsifying agents which have been found 20 suitable are compounds which are soluble in oil but not in water, but which react slowly with alkali to form mono-valent metal soaps. Among such compounds are diglycol oleate, and the soaps formed by the fatty acids with the heavy 25 metals. The reagent by which the emulsion is reversed may be any weak alkali, such as borax or sodium silicate, which is inert to the emulsifying agent at ordinary atmospheric temperatures, but which will react slowly, at the higher 30 temperatures attained in the cooling water when the engine is running, with the result of decomposing the fatty-acid compound and forming a water-soluble soap.

The proportions in which the several components are used are not critical in any case, although changes in proportion will affect the efficiency with which the composition acts. While it is desirable that the operation be completed 35 within a reasonable time, it is not desirable that the reversal of the emulsion occur before the solvent has had time to penetrate the deposits which are to be removed. The optimum proportions for any particular combination can be 40 found readily by experiment.

An effective formula for a cleaning composition in accordance with this invention is as follows:

	Parts by weight
Kerosene, domestic water-white	25 50
Orthodichlorbenzene	25
Borax	5
Diglycol oleate	5
Water	40 55

The borax is dissolved in the water and the other ingredients are dissolved in the kerosene, and the two solutions are then emulsified together, making a stable emulsion.

- 5 When the cleaning composition is to be used, it is added to the water in the cooling system of an engine, and the engine is set in operation so that the water, by its circulation, carries the emulsion to all parts of the system. While the
- 10 water is still cool the oily ingredients, together with the diglycol oleate dissolved in them, penetrate the solid deposits in the system, and dissolve or soften any grease contained in the deposits. When the water is sufficiently heated, by
- 15 the continued operation of the engine, the borax reacts with the diglycol oleate to produce a water-soluble soap, with the result of disintegrating the deposits and producing an oil-in-water emulsion. The cooling water and the emulsified materials
- 20 are then drained from the system, and any remaining solids, having been loosened and disintegrated, may be flushed from the system with additional water.

I claim as my invention:

1. In a composition for the purpose set forth, an emulsion comprising organic oil solvent material insoluble with water, diglycol oleate, and a water solution of borax.

2. In a composition for the purpose set forth, an emulsion comprising kerosene oil, an oil-solvent liquid chlorinated hydrocarbon, diglycol oleate, and a water solution of borax.

3. In a composition for the purpose set forth, the combination of oil-solvent material selected from the class consisting of light hydrocarbon oils, chlorinated hydrocarbons and coal-tar solvents, an oil-soluble soap dissolved in said oil-solvent material and selected from the class consisting of diglycol oleate and the soaps formed by the heavy metals with fatty acids, and an alkali selected from the class consisting of borax and sodium silicate.
